The ornamental design for a rounded display case and associated door, as shown and described.

DESCRIPTION

FIG. 1 is a front perspective view of the claimed rounded display case and associated door, with a handle and shelves shown in broken lines for purposes of illustration only and forming no part of the claimed design;

FIG. 2 is a front plan view thereof;

FIG. 3 is a top plan view thereof (the bottom plan view is a mirror image of the top plan view);

FIG. 4 is a right side view thereof (the left side view is a mirror image of the right side view); and,

FIG. 5 is a rear view thereof.
